United States Patent Office.

W. J. LUDLOW, OF CLEVELAND, OHIO.

Letters Patent No. 86,562, dated February 2, 1869.

IMPROVEMENT IN CORN-SHELLERS.

The Schedule referred to in these Letters Patent and making part of the same.

To all whom it may concern:

Be it known that I, W. J. LUDLOW, of Cleveland, in the county of Cuyahoga, in the State of Ohio, have invented a new and improved Hand Corn-Shell; and I do hereby declare the following to be a full and exact description thereof, reference being had to the accompanying drawings, and the letters of reference marked thereon, of which—

Figure I is a perspective view, showing the manner of its operation;

Figure II, a side elevation; and

Figure III, a cross-section.

The construction of my corn-sheller is as follows:

I first provide a handle of suitable shape. (See A, Figs. I and III.)

A wire, of proper size and length, is coiled on a circle of about three inches diameter, and making three turns, more or less.

The ends of this wire are now bent, so as to come in contact at about one and one-half inch from the coil, and running diagonally from the axis of the coil, thus forming two arms, as shown at *a a'*, Fig. III.

These same ends are now bent at the point of contact, *o*, Fig. III, so as to run parallel, and are separately coiled about the middle of the handle A, as shown at B B', and leaving the ends of the wire projecting on the opposite side of the handle, forming the arms *b b'*, similar to the arms *a a'*.

A second coil, similar to the first, is formed, with the ends of the wire projecting the same distance as the arms of the first coil, parallel with each other, and standing at right angles to the axis of the coil.

The two coils are now interwoven, and the arms of the second made fast to the projecting ends of the wire of the first coil, as shown at *d*, Fig. II.

To each side of the interlocked portions of the coils

is attached a crescent-shaped disk, as shown at F and G in the several figures.

The ends of the inner edge of each disk are bent or turned in opposite directions, so that when brought together, forming the jaws, as shown at F and G, Fig. II, they may operate more effectually in the manner of a screw.

The two disks, on opposite sides of the same coil, are joined together by means of a piece of metal, doubled like the letter V. (See N, Figs. I and III.)

This piece of metal, for greater effect, is set diagonally between the disks.

The plates I I, on the outer part of the coils, serve to strengthen the apparatus, as also to prevent the corn from flying.

The disks, owing to their form, and being placed on opposite sides of the coils, act in the manner of a screw, progressing forward or backward, as they are revolved about the ear of corn. As the forward disks advance, they are pressed between the kernels, which are removed from the cob by the follower N, as it advances.

To operate the sheller, place one end of an ear of corn between the jaws F G. Then, holding the ear E with the left hand, with the right grasp the handle A, and revolve the sheller about the ear. When it has progressed sufficiently far, seize the projecting cob with the right hand, and revolve the sheller with the left.

I claim the combination of the two "jaws," formed of coiled wire, when connected with the handle A, substantially as described, and for the purpose herein set forth.

W. J. LUDLOW.
